UNITED STATES PATENT OFFICE.

EDWARD E. LARSON, OF THOMPSON, IOWA.

ADJUSTABLE REAMER.

1,344,411.

Specification of Letters Patent. Patented June 22, 1920.

Application filed December 13, 1919. Serial No. 344,531.

To all whom it may concern:

Be it known that I, EDWARD E. LARSON, a citizen of the United States, residing at Thompson, in the county of Winnebago and 5 State of Iowa, have invented certain new and useful Improvements in Adjustable Reamers, of which the following is a specification.

This invention relates to improvements in 10 adjustable reamers.

An important object of the invention is to provide a device of the above mentioned character, which is readily and cheaply constructed and in which the cost of main- 15 tenance is greatly reduced.

In adjustable reamers and in many of the tools used in milling machines, longitudinally adjustable blades are provided which when placed in the proper position 20 are held in such position by a wedge. Heretofore it has been the practice to use a wedging screw having threaded engagement with the body of the tool and engaging against a resilient portion which is forced, by the 25 driving in of the wedging screw, into engagement with the cutter to hold the same in place. These screws often break or the threads, either in the body of the tool or upon the screw, strip. This occasions much

30 delay in that new threads must be formed in the body of the tool in the first instance, and in the second instance the threads upon the body of the tool must be thoroughly cleaned and a new screw provided. Then

35 again these screws often break off while engaging in the threads, and in forming the threads a tap is often broken off in the body of the metal. In the first instance the hole must be reborod and retapped for the

40 reception of the new screw, and in the second instance it often becomes necessary to throw away the body of the tool containing the broken tap. Each of these difficulties I have eliminated by forming in the

45 body of the tool instead of a threaded aperture a straight bore which receives a cylindrical bur. This bur is provided with screw threads adapted to receive the threaded portion of the tapered screw.

50 Means are provided for releasably holding these burs within the bores. In event a screw is broken or the threads of the bur or screw strip the bur is simply removed from the bore and a new one inserted. This de-

55 vice also eliminates the waste occasioned by broken taps as above mentioned in that if

a tap breaks within the bur the bur may be discarded with but a slight monetary loss.

Other objects and advantages of the in- 60 vention will be apparent through the fol- lowing description.

In the accompanying drawings wherein for the purpose of illustration is shown a preferred embodiment of my invention and wherein like numerals designate like parts throughout.

Figure 1 is a plan view of a reamer con- 65 structed in accordance with my invention and wherein like numerals designate like parts throughout.

Fig. 2 is an enlarged sectional view show- 70 ing the tapered adjustable key.

Fig. 3 is a section taken on the line 3—3 of Fig. 1, and

Fig. 4 is a detail view of the bur holding 75 pin.

Referring now more particularly to the drawings the numeral 10 indicates the body of a reamer or the like. This body portion is provided with spaced radial slots 11 hav- 80 ing one side thereof tapered as at 12. Seated within the tapered portion of the slots 11 are tapered keys 13 which are provided upon one side thereof with longitudinal serrations 14.

Provided with longitudinal serrations 15 are cutter members 16. It will be obvious that rough adjustments of the cutter mem- 85 bers 16 may be had by shifting the cutter member to advance it one serration or con- versely to withdraw it one serration. When a finer adjustment is desired this may be had by driving the wedge keys 13 in or out as may be desired the wedge keys being pro- 90 vided with a scale 13' by which the amount of adjustment may be observed and governed. The numeral 17 designates a screw mounted in the cutter members to prevent slipping thereof to a position in which any of cutting edges are out of line. It will be obvious 95 that this result may be attained in various ways and I accordingly do not limit myself to the use of a screw.

Provided adjacent the side of each of the slots 11 in which the cutter members 16 reside are slots 18 communicating at their inner ends with bores 19. These slots form a flexible strip 20. Transversely of each slot and centered therewith are provided bores 21 which receive in their upper ends the 110 tapered heads 22 of wedging screws. One or more of these bores and wedging screws

may be provided as desired. Mounted within the bores 22 are cylindrical members 23 having a solid portion 24 provided with a threaded aperture adapted to receive the 5 threaded portion of the screw 22. These cylindrical members are also provided with a transverse slot 25 adapted to receive a pin 26 which is inserted through the bore 19. The pin 26 is provided upon one side thereof 10 with a hump 27 which engages against the side of the bore to prevent accidental slipping of the pin from the bore.

It will be obvious that in event of breakage the cylindrical members are readily removable from and replaceable in the bores 22 and that such removal and replacement can be made without any undue loss of time. It is to be understood that I do not limit the use of these bores for receiving wedging 20 screws to the form of reamer shown as they may be advantageously used in any place where a screw is used that is subjected to a larger amount of strain and usage and therefore liable to be frequently broken.

25 What I claim is:

1. In a reamer, a body portion provided with spaced radial slots, tapered keys disposed within said slots and provided upon one side thereof with serrations, cutter members arranged within said slots and provided with serrations adapted to coact with the serrations in said keys and means for locking said cutter members in position.

2. In a reamer, a body portion provided with spaced radial slots, tapered keys disposed within said slots and provided upon one side thereof with longitudinal serrations and upon the other with a scale, cutter members arranged within said slots and provided 40 with longitudinal serrations adapted to coact with the serrations in said keys, and means for locking said cutter members in position.

3. In a reamer, a body portion provided with spaced radial slots, cutter members arranged within said slots, and means for locking said cutter members in position, embodying bores formed adjacent to one side of and longitudinally parallel with said 45 slots, other slots formed in said body portion and communicating with said bores thereby forming intermediate said body portion and said first named slots, flexible strips, cylindrical members releasably held

within bores formed partially in said flexible 55 strips and partially in said body portion, means disposed within said first named bore for releasably engaging said cylindrical members and retaining them in position and screws having threaded engagement 60 with said cylindrical members and tapered heads engaging said body portion and said flexible strips.

4. In a reamer, a body portion provided with spaced radial slots, tapered keys disposed within said slots and provided upon one side thereof with serrations, cutter members arranged within said slots and provided with serrations adapted to coact with the serrations in said keys, and means for locking 70 said cutter members in position, embodying flexible strips arranged between the body portion and said cutter members, bores formed intermediate said body portion and said flexible strip, cylindrical members 75 releasably held within said bores and screws having threaded portions engaging in said cylindrical members and tapered heads engaging said body portion and said flexible strip.

5. In a reamer, a body portion provided with spaced radial slots, tapered keys disposed within said slots and provided upon one side thereof with serrations, cutter members arranged within said slots and provided with serrations adapted to coact with the serrations in said keys, and means for locking 80 said cutter members in position, embodying bores formed adjacent to one side of and longitudinally parallel with said 85 slots, other slots formed in said body portion and communicating with said bores thereby forming intermediate said body portions and said first named slots flexible strips, cylindrical members releasably held within bores formed partially in said flexible strips and partially in said body portion, means disposed within said first named bore for releasably engaging said cylindrical members and retaining them in position, and screws having threaded engagement 90 with said cylindrical members and tapered heads engaging said body portion and said flexible strips.

In testimony whereof I affix my signature. 105

EDWARD E. LARSON.
